Thos. J. Maguire

UNITED STATES PATENT OFFICE.

HERMAN KEEs, OF DETROIT, MICHIGAN, ASSIGNOR OF TWO-THIRDS TO
GUSTAV FETTERS AND E. HAMBUJER, BOTH OF SAME PLACE.

CAR-COUPING.

SPECIFICATION forming part of Letters Patent No. 355,175, dated December 28, 1886.

Application filed October 28, 1886. Serial No. 217,489. (No model.)

To all whom it may concern:

Be it known that I, HERMAN KEEs, of Detroit, in the county of Wayne and State of Michigan, have invented new and useful Improvements in Car-Couplings; and I do hereby declare that the following is a full, clear, and exact description thereof, reference being had to the accompanying drawings, which form a part of this specification.

10 This invention relates to certain new and useful improvements in car-couplings.

The invention consists in the peculiar construction and arrangement of a latch in the draw-head adapted to engage with a harpoon coupling-link, and in the construction, arrangement, and combination of the various parts, all as more fully hereinafter set forth.

Figure 1 is a perspective view of my improved coupler. Fig. 2 is a cross-section 20 through the latch. Fig. 3 is a plan.

In the accompanying drawings, which form a part of this specification, A represents a hollow draw-head provided with a circular bell-mouth, B, terminating in a throat, as in the 25 ordinary manner.

C is a latch rigidly secured upon a shaft, D, which is properly journaled in ears *a* upon the side of the draw-head. The inner end of this shaft terminates in an actuating-lever, E, 30 which extends across the end of the car, as shown, and is provided with the counter-weighted arm F.

G is a stop-link, through which one end of the actuating-lever E projects.

35 The free end of the latch C is provided with a weight, c, and this latch is designed to enter a transverse slot in the top of the draw-head, and to partially close the throat of the same.

H is the coupling link or bar, which is of the harpoon class, as shown.

40 In practice, upon two cars coming together, with this device the head of the coupling-bar enters the bell-mouth, and impinging against the lower edge of the latch elevates the same till the head has passed such latch, when the latter by gravity falls and engages with such head and the cars are coupled together. To uncouple, the brakeman operates the lever E, in such manner as to elevate the latch, and thus free the same from its engagement with 45 the coupling-link. The stop G limits the throw of the actuating-lever, so that the counter-weighted arm thereof will insure a return of the latch to its closed or normal position.

50 Should one or more cars run off the track or be upset, the weight of the lever F should be sufficient to counteract the weight of the latch and cause the cars to uncouple.

55 What I claim as my invention is—

1. In a car-coupling, the combination of the 60 hollow draw-head A, provided with a gravity-latch, C, and an actuating-lever, E, provided with a counter-weight, F, substantially as described.

2. In a car-coupling, the combination of a 65 hollow draw-head, A, transverse gravity-weighted latch C, shaft D, lever E, provided with a weighted arm, F, and the stop-link G, engaging one arm of said lever with a coupling-bar, H, when constructed, arranged, and 70 operating substantially in the manner and for the purposes set forth.

HERMAN KEEs.
